UNITED STATES PATENT OFFICE.

MARION CHAPPELL, OF LONDON, ENGLAND.

DESIGN FOR A PIANO-CABINET.

SPECIFICATION forming part of Design No. 27,230, dated June 15, 1897.

Application filed April 27, 1897. Serial No. 634,175. Term of patent 7 years.

To all whom it may concern:

Be it known that I, MARION CHAPPELL, a subject of the Queen of Great Britain, residing at London, England, have invented and produced a new and original Design for Piano-Cabinets, of which the following is a full, clear, and exact description, reference being had to the accompanying drawing, showing the same.

10 The figure of the drawing shows the back of a piano showing my design.

The leading feature of my design consists of an ornamental extension built out from the back of the piano, the outlines of said extension when viewed in elevation forming an ornamental case having a number of compartments and the whole falling within the outlines of the instrument.

15 The case 1 of the piano is of regular form and size and has a centrally-projecting desk-section 2, adapted to be hid from view by the

hinged lid 3, which when down serves as a writing-desk. To either side of said desk-section are two compartments 4 5 of quadrant form and ornamented by paneling 6, a lower 25 scrollwork 7, and tops 8, and these, together with the shelf 9, having the recessed portion 10 and fancy molding 11, forming a highly-ornamented cabinet aside from its apparent utility.

20 What I claim is—

The design for a piano-cabinet herein shown and described, the same comprising the central desk-section having the quadrant-shaped compartments on either side and the whole 35 bordered by a fancy molding and scrollwork.

In testimony whereof I affix my signature in the presence of two witnesses.

MARION CHAPPELL.
